(57) **CLAIM**

The ornamental design for a tool for cleaning an aerosol-generating device, substantially as shown and described.

DESCRIPTION

FIG. 1 is a perspective view of a tool for cleaning an aerosol-generating device, showing our new design;
 FIG. 2 is another perspective view of the tool;
 FIG. 3 is a front elevational view of the tool;
 FIG. 4 is a rear elevational view of the tool;
 FIG. 5 is a left side elevational view of the tool;
 FIG. 6 is a right side elevational view of the tool;
 FIG. 7 is a top plan view of the tool;
 FIG. 8 is a bottom plan view of the tool; and,
 FIG. 9 is an enlarged view of the region 9 of FIG. 1, showing a signal light on the tool.

The broken lines consisting of evenly spaced dash lines in the drawing depict portions of the tool for cleaning aerosol generating device that form no part of the claimed design. The broken lines consisting of short and long dash lines encircling the enlarged detail views are for annotative purposes that form no part of the claimed design.
